(57) **CLAIM**

The ornamental design for an upper structure of utility vehicle, as shown and described.

DESCRIPTION

FIG. 1 is a front elevational view of an upper structure of utility vehicle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a front and right-side isometric view thereof; and, FIG. 7 is a rear and right-side isometric view thereof.

In the drawings, the broken lines and the light-grayed out portions of the design depict environmental subject matter only and form no part of the claimed design.
